(57) **CLAIM**

The ornamental design for a gravity fed dispenser, or the like, as shown and described.

DESCRIPTION

FIG. 1 is a front elevational view of a gravity fed dispenser or the like, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top and right front perspective view thereof;

FIG. 8 is a front elevational view of second embodiment of the gravity fed dispenser;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a top and right front side perspective view thereof.

The broken line showing in the figures is for illustrative purposes only and forms no part of the claimed design.
